UNITED STATES PATENT OFFICE.

ROBERT MARCHER, OF NEW YORK, N. Y.

BURNISHING MOLDINGS.

Specification of Letters Patent No. 24,319, dated June 7, 1859.

To all whom it may concern:

Be it known that I, ROBERT MARCHER, of the city, county, and State of New York, have invented a new and useful Machine for 5 Burnishing Moldings Covered with Gold or other Leaf Used for Such Purposes; and I do hereby declare that the following is a full, clear, and exact description of the same, reference being had to the annexed 10 drawings, making a part of this specification, in which—

Figure 1, is an elevation of my invention. Fig. 2, is a transverse vertical section of do., taken in the line x, x , Fig. 1.

15 Similar letters of reference indicate corresponding parts in the two figures.

The object of this invention is to supersede the manual operation of burnishing moldings by expediting the work to a very 20 great degree and completing the same in a more uniform and perfect manner.

The invention consists in attaching the burnishing tool to a reciprocating slide or carriage and having the molding to be burnished fitted between center points, or in a 25 lateral sliding frame, either or both, whereby by the desired result is attained.

To enable those skilled in the art to fully understand and construct my invention I 30 will proceed to describe it.

A, represents a framing which may be constructed in any proper way and B, B, are two parallel bars placed longitudinally thereon, and having grooves a , made in their 35 inner sides, one in each, in which the sides of a plate or carriage C, are fitted, the grooves a , forming guides for said plates. This is clearly shown in Fig. 2.

The plate C, is allowed to slide freely between the bars B, B, and it has an upright D, attached, in which a swivel eye E, is fitted. This eye E, is formed in a rod b, which passes horizontally and loosely 40 through the upright D, but which may be secured rigidly therein when desired by means of a thumb nut c, which is placed on a screw thread on one end of the rod b. In the opposite end of the rod b, a screw d, passes.

45 Into the eye E, a rod F, passes and through the rod F, near its outer end an eye G, is attached, which is arranged precisely similar to the eye E, it being secured rigidly to the rod F, when desired by a 50 thumb nut e, on one end of the eye rod f,

said rod having a screw g, passing into its opposite end.

Into the eye G, of rod F, a rod H, is fitted, in the lower end of which a burnishing tool I, is secured.

60 On the upper part of the framing A, and at each end a horizontal rod J, is placed. These rods may be placed in bearings K, that are either rigidly attached to the framing A, or are fitted on ways h, to admit of a 65 lateral movement of the same. At the inner end of each rod J, a point i, is formed.

L, represents a bar which is suspended from the rods J, by rods M, the upper ends of which have eyes formed on them to fit 70 on the rods J, as shown clearly in Fig. 1. The rods m, having nuts α , on their lower ends to admit of the raising and lowering of bar L, as may be desired.

75 The operation is as follows:—The molding N, to be burnished is placed on the bar L, and centered between the points i, i, and a reciprocating motion is given the plate or carriage C, by any motive power. If the molding N, has a face which forms the part 80 of a cylinder as represented in the drawings the points i, i, enter the ends of the molding coincident with the axis of a cylinder of which the face of the molding forms a part. By turning the nuts α , the bar L, 85 may be raised or lowered so that moldings with either convex or concave surfaces may be properly centered and also moldings of varying thicknesses. As the burnishing tool I, moves back and forth, the molding is 90 turned intermittently between the points i, i, until the whole of its face surface is acted upon. If the face of the molding be of an ogee or similar wave form it is centered a plurality of times so that the varying 95 curved surface of both the convex and concave portion, may be turned concentrically beneath the burnisher, or nearly so, the self adjusting feature or property of the burnisher compensating for any deviation from 100 a concentric movement. In case the face of the molding is formed of a curved and plane surface, the plane portion of the surface is moved laterally underneath the burnisher in consequence of the bearings K, being allowed to slide on the ways h.

105 In consequence of having the burnisher I, connected to the upright D by means of the adjustable rods F, H, a requisite degree of adjustability is allowed so that the burnisher 110

may conform to the varying form of the surface of the molding. If the moldings have an entirely plane surface the eye E, may be rigidly attached to the bar D, by screwing up the nut d, and the rod F, may be rigidly secured in E, by screwing up the screw d, the eye G, is also rigidly secured to the rod F, but the rod H, is permitted to slide freely up and down in eye G, to allow the burnisher to conform to the inequalities of the surface of the molding. In cases where moldings have irregular curved surfaces, the burnisher may by relaxing the nuts e, e, have a free movement so as to conform properly to the face of the molding, or be self adjusting.

I do not confine myself to any particular mode of attaching the burnisher I, to the reciprocating plate or carriage C, for that

may be done in various ways. The molding N, may be turned by hand or any automatic mechanism may be employed for the purpose.

Having thus described my invention what I claim as new and desire to secure by Letters Patent, is—

Attaching a self-adjusting burnisher I, to a reciprocating plate or carriage C, when used in connection with a molding N, suspended and attached to the machine in the manner as shown, or in any equivalent way to admit of being acted upon by the burnisher for the purpose set forth.

ROBT. MARCHER.
